SPECTACLE FRONT

Robert Passet, Vincennes, France, assignor to Societe Industrielle de Lunetterie, Paris, France, a French company

Application April 19, 1955, Serial No. 35,576

Term of patent 14 years

(Cl. D57—1)

Fig. 1

I claim:

The ornamental design for a spectacle front, as shown.
